UNITED STATES PATENT OFFICE.

JOSEPH VOGT, OF RICHMOND, MINNESOTA.

BLOCK-MACHINE.

1,379,733.

Specification of Letters Patent. Patented May 31, 1921.

Application filed April 19, 1920. Serial No. 375,061.

To all whom it may concern:

Be it known that I, JOSEPH VOGT, a citizen of the United States, residing at Richmond, in the county of Stearns and State of Minnesota, have invented certain new and useful Improvements in Block-Machines, of which the following is a specification, reference being had to the accompanying drawings.

10 This invention relates to certain improvements in block machines and has relation more particularly to a machine of this general character especially designed and adapted for use in connection with cementitious or other plastic material, and an object of the invention is to provide a novel and improved machine of this general character embodying tamps arranged in opposed relation and adapted to be operated in unison to impose the requisite pressure upon the material within the mold box.

It is also an object of the invention to provide a machine of this general character including a mold or box provided with a movable wall and wherein the various operations of the machine are accomplished automatically when said movable wall is in its closed or applied position.

Another object of the invention is to provide a novel and improved device of this general character embodying relatively movable tamps working within a mold or box, together with driven means for operating said tamps and wherein the mold or box is provided with a removable wall or top which, when moved into open position, causes the driven means to become inoperative and which, when in closed or applied position, permits the driven means to become operative.

Another object of the invention is to provide a novel and improved machine of this general character including a mold or box in which is positioned a movable pallet, together with means to automatically eject the pallet and the article thereon from within the mold or box after the molding operation is completed.

A still further object of the invention is to provide a novel and improved machine of this general character including a mold or box embodying a movable top and side wall, together with means for exerting the requisite pressure upon the material within the mold or box and which means is under con-

trol of the movable top and wherein means are provided for locking the movable top and side wall of the mold or box in working relation during a molding operation.

The invention also has for an object a novel and improved machine of this general character wherein the various operations necessary for the production of the block or other article after the material has been applied within the mold or box and said mold closed, are performed in an automatic manner from a driven element, together with means for rendering the driven element inoperative and thereby stopping the machine at the will of the operator as unforeseen requirements of practice may necessitate.

It is also an object of the invention to provide a novel and improved machine of this general character of a portable type so that the same can be readily and conveniently transported as desired and particularly in an event when it is preferred to produce the blocks, or the like, close to the building operation.

The invention consists in the details of construction and in the combination and arrangement of the several parts of my improved machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of a machine constructed in accordance with an embodiment of my invention and with portions broken away for clarity in disclosure;

Fig. 2 is a view in top plan, with certain of the parts omitted, of the structure as illustrated in Fig. 1;

Fig. 3 is a longitudinal vertical sectional view taken through the machine as herein disclosed and at substantially the transverse center thereof;

Fig. 4 is an enlarged fragmentary view partly in elevation and partly in section, illustrating in detail the driving means for the machine;

Fig. 5 is a fragmentary view partly in sec-

tion and partly in top plan of the structure illustrated in Fig. 4 with the worm or spiral gear omitted;

Fig. 6 is an enlarged fragmentary view 5 partly in side elevation and partly in section illustrating in detail certain of the structure concomitant to the mold or box for holding the top wall or cover and the movable side wall thereof in closed or working 10 position and for moving the same into open or inoperative position;

Fig. 7 is a fragmentary view partly in elevation and partly in section illustrating in detail one of the tamps herein employed 15 and operating within the mold or box;

Fig. 8 is a fragmentary view partly in section and partly in elevation, illustrating in detail a portion of the structure for controlling the operative connection between 20 the driven and driving elements for operating the machine;

Fig. 9 is a view similar to Fig. 8 but showing certain of the parts in a second position;

Fig. 10 is a view in perspective of a pawl 25 or dog coacting with the ejector mechanism detached; and Fig. 11 is a view similar to Fig. 3 but showing certain of the parts in a second position and several of said parts 30 indicated by dotted lines.

As disclosed in the accompanying drawings, a plurality of channel beams 1, preferably four in number, are arranged in parallelism and are suitably connected adjacent 35 their opposite ends by the transverse members or strips 2 and 3. By this means, a unitary structure is provided which constitutes the body of my improved machine and in order that this body may be readily 40 transported in accordance with the requirements of practice, I find it of advantage to provide at points adjacent to the opposite ends of such body the wheels 4. By having the body portable, the same may be 45 readily taken from one operation to another when it is desired to produce the blocks at the work. Also interposed between each pair of outer beams 1 are the bracing or reinforcing rods 5.

Rotatably supported by certain of the beams 1 inwardly of but in close proximity to the transverse member or strip 3 is a shaft 6 and the portion of said shaft 6 between the central beams 1 is provided with 55 the crank 7. Fixed to the shaft 6 between a pair of adjacent side beams 1 is a worm or spiral gear 8 in mesh with a worm 9 carried by the longitudinally disposed shaft 10. This shaft 10 is rotatably supported 60 by the bearings 11 carried by the plate 12 bridging the space between said side beams 1 and suitably anchored thereto. The shaft 10 extends beyond the adjacent end of the body and underlies a transversely disposed 65 angle beam 14, having one of its flanges

disposed downwardly. An end portion of the beam 14 is pivotally engaged, as at 15, with an outstanding arm 16 carried by the adjacent end portion of the side beam 1 remote from the shaft 10 whereby the beam 14 has swinging movement in substantially a horizontal path. The opposite end portion of the beam 14 is operatively engaged, as at 17, with the rear portion of a forwardly directed pitman 18. The opposite 75 or forward end portion of the pitman 18 is operatively engaged, as at 19, with a depending rock arm 20 carried by an end portion of a transversely disposed shaft 21. The shaft 21 is supported by the bearing 22 80 depending from each of the beams 1 and the opposite end of said shaft 21 is provided with an upstanding rock arm 23. The upper end portion of the rock arm 23 has pivotally engaged therewith an end portion 85 of an elongated rod 24, extending longitudinally of the machine and in a direction forwardly thereof or in a direction away from the shaft 6. The rod 24 is disposed through a guide member 25 carried by the 90 adjacent side beam 1 and terminates in a hand grasp 26. By imparting pull upon the rod 24, the beam 14 will be caused to swing in a direction away from the body for a purpose which will hereinafter be 95 specifically mentioned and which operation is adapted to be performed in the event of an emergency and which operation is manually effected at the will of the operator.

27 denotes a clutch member interposed 100 between the beam 14 and adjacent end of the body and keyed to the shaft 10 for rotation therewith but capable of sliding movement longitudinally of said shaft. The clutch member 27 includes a hub 28 which 105 is operatively engaged with a depending flange of the beam 14 so that as the beam 14 is swung, said member will be caused to move along the shaft with said beam 14 and in the same direction. While this operative connection between the depending flange of the beam 14 and the hub 28 may 110 be effected in any desired manner, it is preferred that the depending flange of the beam 14 be provided with a slot 29 of requisite dimensions with the portion of said depending flange defining said slot extending within an annular groove 30 produced in the periphery of the outer end portion of the hub 28.

The shaft 10 extends outwardly beyond the beam 14 and terminates in a head 31. Interposed between the head 31 and the opposed end of the hub 28 of the clutch member 27 is a coil spring 32 encircling the 125 shaft 10 and which operates to constantly urge the member 14 inwardly so that the clutch 27 will normally be in operative engagement with the pulley 33 loosely mounted upon the shaft 10. The pulley 33 is 130

adapted to be suitably coupled with any desired source of power, preferably a traction engine or other portable power generating unit.

5 The forward end portion of the body of the machine or that end portion remote from the shaft 6 has extending outwardly from the beams 1 the elongated arms 34 with the side arms 34 of a length greater than the intermediate arms. Extending upwardly from the inner end portions of the arms 34 and anchored thereto in any desired manner is the rigid or stationary side plate 35 for the mold or box. 36 denotes the second 10 side plate for the mold or box and which plate has secured at its opposite end portions the vertically disposed swinging arms 37. The central portion of each of the arms 37 is inwardly offset, as at 38, and pivotally 15 engaged, as at 39, with an adjacent arm 34 so that when pull is imposed upon the lower end portion of the arm 37, the plate 36 will be caused to swing outwardly and downwardly into substantially a horizontal 20 position and the offset portion 38 of each of said arms 37 assures said plate 36 when in its lowered position to be arranged below the upper edges of the arms 34 so that no obstruction will be given to the outer or 25 ejecting movement of the pallet P. The pallet P snugly fits between the plates 35 and 36 when the box or mold is in assembled relation and said pallet is of a length to extend beyond the side arms 34. The upper 30 longitudinal marginal portions of the plates 35 and 36 are beveled so that when the mold or box is being filled, the collection thereon of material is prevented. The mold or box also includes a cover or top C which, when 35 in working position, rests upon the upper or beveled edges of the plates 35 and 36. The cover or top C is also substantially the same length as said plates 35 and 36. The cover or top C is suitably secured to the inner edges of the transversely disposed 40 irons or members 40 and in predetermined spaced relation along the top or cover C with the end irons or members 40 of a length greater than the length of the intermediate irons 40. The inner end portions 45 of the irons or members 40 are continued by the downwardly directed extensions or arms 41 on a predetermined angle and are hingedly connected, as at 42, with the upstanding lugs 50 50 carried by the inner portions of the arms 34. Each of the arms 41 is also provided with the strengthening or bracing arms 44 adapted to contact with the outer face of the stationary or rigid plate 35 during a 55 molding operation and whereby said plate 35 is further held to overcome the pressure created within the mold or box. The central extensions or arms 41 are of a length greater than that of the end extensions or 60 arms 41 and said central arms of exten- 65

sions 41 have their lower or free end portions connected by a transversely disposed rod 45. The pivoted connection 42 of the arms 41 permits the cover or top C to have swinging movement in a vertical path and 70 in a direction toward or from the completed mold or block and the outward movement of said cover or top C is adapted to be automatically attained while the inward or closing movement is adapted to be performed manually, as will hereinafter be 75 more fully explained.

The end irons or members 40 are provided with depending lugs 46 which are adapted to coact with the outer longitudinal marginal portion of the plate 36 to lock the same against outward movement when the cover or top C is in applied position. Said end members 40 also have their outer or free end portions continued by 80 the downwardly directed arms 47 substantially at right angles thereto and which, when the cover or top C is in closed position, terminate below and in close proximity to the side arms 34. The lower end portion 85 of each of the arms 47 has pivotally engaged therewith a latch 48 which engages beneath an outwardly directed lug 49, or the like, carried by the adjacent arm 34. By this means, the cover or top C is effectually 90 locked in working position. The latches 48 are automatically disengaged from the lugs 49 in a manner which will hereinafter be 95 more particularly referred to.

The pallet P, hereinbefore referred to, 100 rests directly upon the arms 34 and is disposed transversely of the body structure and movable longitudinally of the pallet at opposite ends of the mold or box are the tamps T which, upon inward movement, operate 105 to compress the material placed within the mold or box. Each of the tamps T rests upon a pallet P and comprises an upstanding plate 50 having its upper edge beveled to prevent accumulation of material 110 thereon and of a configuration to snugly engage within the assembled mold or box. The lower marginal portion of the plate 50 is defined by an outstanding plate 51 which contacts and rides upon the upper face of 115 the pallet P and the central portion 52 of said plate 51 is cut-away so that the material which may be collected upon said plate is materially reduced with the resultant obstruction or hindrance which would otherwise result from such accumulated material substantially eliminated.

The central portion of the plate 50 of each of the tamps T is provided with an outstanding arm 53 and pivotally engaged with 125 the outer end portion of said arm 53 is a rearwardly disposed pitman A, herein disclosed as comprising two relatively spaced elongated members 54 and arranged in parallelism and substantially co-extensive in 130

length. Disposed between said members 54, at substantially the longitudinal center of each of the pitmen A, is an extended end portion of the transversely disposed member 2 and with which said members 54 of the pitman A are pivotally engaged, as at 55, whereby said pitman A is mounted for swinging movement in substantially a horizontal path. Extending between the inner 10 or rear end portion of the members 54 of each of the pitmen A is an end portion of an inwardly directed arm 56 and pivotally engaged therewith, as at 57. The inner end portions of the arms 56 are pivotally engaged with a vertically disposed pin 58 extending through the central portion of a slide 59. The slide 59 is supported for rectilinear movement between the central beams 1. The rear portion of the slide 59 15 is provided with an upstanding lug or block 60 with which is pivotally engaged an end portion of a pitman 61, having its opposite end portion operatively engaged with the crank 7 hereinbefore referred to, so that as 20 the shaft 6 rotates, the requisite rectilinear movement will be imparted to the slide 59. As the slide 59 moves forwardly, the tamps T will be forced inwardly of the mold or box to compress the material placed therein 25 and vice versa. The material placed within the mold or box B is preferably semi-plastic and particularly cementitious. The outer end portion of the plate 51 of each of the tamps T is provided with an inwardly directed elongated arm 62 coplanar therewith 30 and which has its outer or free end portion pivotally engaged with a link 63 extending inwardly on a predetermined incline and pivotally engaged with an outstanding lug 35 64 carried by the adjacent side beam 1. Each of the links 63, at a desired distance intermediate its ends, is provided with an upstanding lug 65 through which is loosely 40 directed an end portion of a rod 66. The opposite end portion of the rod 66 is pivotally engaged with an outstanding lug 67 45 carried by the adjacent side beam 1 at a point in advance of the lug 64 but in relatively close proximity thereto. Encircling the rod 66 and interposed between the lugs 65 and 67 is a coil spring 68 which operates 50 to constantly swing the link 63 rearwardly, resulting in the inner edge of the plate 51 of the tamp having close contact with the rigid or stationary plate 35 of the box or mold yet permitting the tamp to have desired rectilinear movement within the mold or box.

The lower end portion of the pin 58 is provided with a head 69 with which is pivotally engaged an end portion of a forwardly disposed and downwardly inclined bar 70. The bar 70, at a predetermined point between its ends, is provided with a notch 71 65 having its inner end α abrupt to afford a

shoulder or stop and its remaining portion b disposed on an incline. As the slide 59 moves forwardly to force the tamps T within the box or mold, the lower edge of the bar 70 rides over the rod 45 and just before the 70 tamps T reach the limit of their inward or compression movement, the shoulder α engages the rod 45 and thereby causes the cover or top C to swing upwardly into an open position. The lower or free end portion of the bar 70 passes freely through a slotted guideway 72 carried by and depending from the side plate 36.

However, before the cover or top C can swing upwardly into open position, it is 80 necessary that the latches 48 be moved into a releasing position. Each of the latches 48 is provided with a tail 73 with which is pivotally engaged the lower end portion of an upstanding bar 74. The upper end portion of the bar 74 is pivotally engaged, as at 75, with the lower end portion of a vertically disposed bar 76. The bar 76 substantially midway its length is pivotally engaged, as at 77, with the outer end portion 90 of a side or end iron or member 40. The upper end portion of the bar 76 is continued by a rearwardly directed extension or arm 78 substantially at right angles thereto. Pivotally engaged with the free end portions of the extensions or arms 78 are the end portions of the rods 79, said end portions of the rods 79 being directly engaged with a bar 80 connecting the outer or free end portions of the extensions or arms 78. The rods 100 79 are disposed inwardly and upwardly in convergence and the converging end portions thereof are continued by the rearwardly and upwardly directed rod 81. The rear or free end portion of the rod 81 is 105 freely disposed through a sleeve 82, and pivotally supported, as at 83, at a point substantially midway its length, are the upper end portions of an upstanding forwardly inclined rock arm 84. In threaded engagement with the free end portion of the rod 81 110 is a nut 85 which constitutes a stop for contact with the inner or adjacent end of the sleeve 82. The rock arm 84 is carried by a shaft 86 disposed transversely of the machine and rotatably supported by the upstanding posts 87 carried by the central beams 1. The lower end portion of the rock arm 84 is provided with a depending trigger 88 positioned in the path of travel of the 120 upstanding trip 89 carried by the pitman 61. The crank 7 rotates upwardly and forwardly and at a predetermined point before the pitman reaches the limit of its forward movement, the trip 89 engages the trigger 88 and 125 thereby swings the arm 84 rearwardly, resulting in an upward pull upon the extensions or arms 78 and a corresponding pull upon the bars 74 whereby the latches 48 are 130 swung into a releasing or inoperative posi-

tion. The trip 89 operates to release the latches 48 just before the bars 70 operate to throw the cover or top C into its raised or open position. The latches 48 are released 5 and the cover or top C raised or elevated upon the forward stroke of the pitman 61 and said cover or top C is thrown back beyond the center so that it can only be returned manually. When the pitman moves 10 rearwardly, the bar 70 will freely ride over the rod 45 and just before the pitman 61 reaches the limit of its return movement, the clutch member 27 is disengaged from the pulley 33 through the instrumentality of the 15 actuator bar 90. The forward end portion of the bar 90 is pivotally engaged, as at 91, to an arm 92 depending from the end portion of the pitman 61 operatively engaged with the crank 7 and the rear or outer end 20 portion of the bar 90 is provided with a shoulder 93 which assumes a position by gravity to contact with a block 94 mounted upon a table 95 suitably secured to the upper face of the beam 14. By this means, it 25 will be perceived that as the actuator bar 90 moves rearwardly, the contact of the shoulder 93 with the block 94 will swing the beam 14 in a direction away from the body of the machine and thereby move the clutch member 27 along the shaft 10 out of operative 30 engagement with the pulley 33 and will hold said clutch member 27 in such position until the actuator bar 90 is disengaged from the beam 14. The upper marginal portion of 35 the bar 90 is continued by an elongated arm or extension 96 co-planar therewith and which rides within a guide groove or slot 97 formed in the upper face of the block 94. The arm or extension 96 is of a length to 40 rest upon the block 94 upon the continued stroke of the pitman 61 after the crank 7 has passed a vertical center above the shaft and whereby the shoulder 93 engages the block 94 just before the crank 7 reaches substantially a horizontal center and is rearwardly directed. 45

Rotatably supported by the table 95 is a shaft 98 extending transversely of the extension or arm 96 and underlying the same. Fixed to the shaft 98 directly below the extension or arm 96 is a wing 99 and which wing, when raised, contacts with the extension or arm 96 and operates to raise the actuator bar 90 sufficiently to disengage the shoulder 93 from the block 94 whereupon 50 the spring 32 automatically returns the clutch 27 into working engagement with the pulley 33 and the machine performs its function. The wing or plate 99 operates 55 to elevate the actuator bar 90 when the cover or top C is returned to closed position and which operation is accomplished by the rod 100 extending longitudinally of the machine and having one end portion freely 60 engaged with the bar 80 and having its 65

opposite end portion freely disposed through the sleeve 101 suitably supported substantially midway its length, at 102, with the upper or free end portion of an upstanding and forwardly inclined rock arm 103 70 carried by an end portion of a shaft 98. As the cover or top C is automatically raised, the free end portion of the rod 100 freely slides through the sleeve 101 until engaged by the stop 104 carried by the rod 100 at a predetermined point inwardly of the sleeve 101. This results in the rock arm 103 being moved rearwardly with a resultant lowering of the wing or plate 99 so that the actuator rod 90 drops into a 75 position whereby the shoulder 93 thereof will engage the block 94 to swing the beam 14 outwardly. When the cover or top C is in its raised or open position, the material to be compressed is placed within the mold 80 or box upon the applied pallet P and the cover or top C manually returned to closed position. Upon this movement of the cover or top C, the rod 100 will move forwardly and just before said cover or top C assumes 85 its complete closed position, a stop 105 carried by the rod 100 outwardly of the sleeve 101 will contact with said sleeve and thereby raise or elevate the wing or plate 99, resulting in the shoulder 93 of the actuator bar 90 disengaging the beam 14 whereupon the clutch member 27 will automatically return into working engagement with the pulley 33. In order to limit the forward 90 movement of the rock arm 103, I find it of advantage to provide a stop 106 secured to the cross member or strip 3. I also find it of advantage to have each of the stops 104 and 105 adjustable lengthwise of the rod 100 so that said stops may be properly positioned on the rod 100 as the necessities of 95 practice may require. 100

When the cover or top C and the side plate 36 are moved into their open position, it is of importance to provide means for 110 ejecting the pallet P and the article molded thereon and, as herein embodied, the means for ejecting the pallet also comprises the means for swinging the side plate 36 into open position. 115

The lower end portion of each of the arms 37 has pivotally engaged therewith an end portion of an inwardly disposed lever 107 which is also pivotally engaged at a material point inwardly of its opposite end 120 with an end portion of a lever 108. The lever 108 is also pivotally engaged with the adjacent arm 34. The pivotal connection 109 affords a brake joint between the levers 107 and 108 and said levers are held against movement in one direction beyond center by the coacting pin and notch, as indicated at 110, carried by said levers 107 and 108. 125

Each of the levers 108 is provided at its 130

outer end portion with an upstanding cam member 111 with which engages an end portion of a slide 112 supported for endwise movement by the bearings 113 carried by 5 the adjacent side beam 1.

As the slides 112 move forwardly, the same cause the levers 108 to swing downwardly pulling the levers 107 inwardly whereupon the plate 36 is moved into an 10 open or lowered position. In order to facilitate this operation, I find it of advantage to interpose between the lower end portion of each of the arms 37 and the adjacent side beam 1, at a point inwardly of the arm 37, a 15 retractile coil spring 114. The springs 114 are insufficient to swing the plate 36 but materially reduce the strain to be imposed by the slides 112.

Each of the slides 112 has coacting there- 20 with a retractile member or spring 115 which serves to normally maintain the same when at the limit of its movement in a direction away from the cam 111 and which movement is determined by the upstanding 25 shoulder 116 carried by the slide 112. The upper face or edge of the shoulder is inclined downwardly and forwardly and is continued within a notch 117 produced in the upper marginal portion of the slide 112 30 and which notch provides a stop or shoulder 118. A gravity pawl 119 is adapted to engage the stop or shoulder 118 to move the slide 112 forwardly. In the present embodiment of my invention, the outer end 35 portion of the pawl 119 is provided with a loop 120 into which extends an end portion of a rock lever 121. The lever 121 is pivotally engaged with the outer end of the pawl 119 and is supported, as at 122, midway its 40 length for rocking movement in a vertical direction. The cover or top C is provided with the longitudinally spaced bearings 123 which rotatably support a shaft 124. The shaft 124, at its opposite ends, is provided 45 with the rearwardly directed arms 125 which are adjustably connected, as at 126, with the forward end portions of the levers 121. As the cover or top C is raised or moved forwardly, the arms 125 will cause 50 the lower portions of the levers 121 to swing downwardly and forwardly and the pawl or dog 119 carried by each of said levers 121 will engage the stop or shoulder 118 and move the slide 112 forwardly. The forward 55 movement of the slide 112 first effects an opening of the side plate 36 and the continued movement of the slide causes the same to contact with an extended end portion of the pallet P and partially eject the 60 same a distance sufficient to permit said pallet to be readily withdrawn by a workman or workmen. After the pallet P has been ejected a predetermined distance by the slides 112, each of the levers 121 will have 65 swung sufficiently to cause the shoulder 127,

carried by the lower end portion thereof, to engage the outer end portion of the loop 120 of the pawl 119 whereupon said pawl or dog is automatically disengaged from the shoulder or stop 118, resulting in the slide 70 112 being automatically returned to the limit of its inward movement through the instrumentality of the spring 115.

I find it also of advantage to engage with the lower end portion of each of the arms 75 37 a retractile member or spring 128 secured to the adjacent arm 34 at a point in advance of said arm 37. The spring or member 128 operates to prevent the plate 36 from being thrown downward into open position at too great a speed or with excessive force. In other words, the spring or member 128 80 serves to substantially balance the plate 36 when being moved into open or lowered position.

I also find it of advantage to connect the upper end portions of the posts 87 by the rearwardly and upwardly inclined arch member 129 which serves as a stop to limit the rearward swinging movement of the 90 arm 84.

The outer end portions of the arms 37 are connected by the spacing or tie rod 130 whereby the structure is materially strengthened or reinforced.

From the foregoing description, it is thought to be obvious that a machine constructed in accordance with my invention is particularly well adapted for use by reason of the convenience and facility with 100 which it may be assembled and operated, and it will also be obvious that my invention is susceptible of some change and modification without departing from the principles and spirit thereof, and for this reason I 105 do not wish to be understood as limiting myself to the precise arrangement and formation of the several parts herein shown in carrying out my invention in practice except as hereinafter claimed.

I claim:

1. A block press comprising, in combination, a mold box including a removable top, opposed tamps operating within the box, means for substantially reciprocating said 115 tamps, automatic means operated by said first named means for moving the top into open position, and means operating upon opening movement of the top to render inoperative the means for moving the tamps. 120

2. A block press comprising, in combination, a mold box including a removable top, opposed tamps operating within the box, means for substantially reciprocating said 125 tamps, automatic means operated by said first named means for moving the top into open position, and means operating upon opening movement of the top to render inoperative the means for moving the tamps, the means for moving the tamps becoming 130

operative when the top is returned to closed position.

3. A block press comprising, in combination, a mold box embodying a movable wall, 5 a tamp working within the mold box, means operated by said first named means for operating the tamp, automatic means for moving the movable wall into open position after the tamp has completed its pressure 10 stroke, and means under control of the movable wall to render the operating means for the tamp inoperative when said movable wall has moved to a predetermined extent into open position.
- 15 4. A block press comprising, in combination, a mold box, a tamping means working therein, means for operating the tamping means operated by said first named means, automatic means for rendering inoperative 20 the operating means for the tamping means after said tamping means has completed compression action and the operating means therefor is rendered inoperative.
5. A block press comprising, in combination, 25 a mold box including a movable top and a movable side wall, means common to the movable top and movable side wall for locking the same in working relation, tamping means working within the box, means 30 for operating the tamping means, and mechanism operable by the last named means for releasing the movable top and movable side wall and moving the same into open position after the tamping means has completed 35 compression action within the box.

6. A block press comprising, in combination, a mold box including a movable top and a movable side wall, means common to the movable top and movable side wall for locking the same in working relation, tamping means working within the box, means for 40 operating the tamping means, mechanism operable by the last named means for releasing the movable top and movable side 45 wall and moving the same into open position after the tamping means has completed compression action within the box, and means under control of the movable top for rendering the operating means for the tamping 50 means inoperative when said movable top has reached a predetermined open position.

7. A block press comprising, in combination, a mold box including a movable top 55 and a movable side wall, means common to the movable top and movable side walls for locking the same in working relation, tamping means working within the box, means for operating the tamping means, 60 mechanism operable by the last named means for releasing the movable top and movable side wall and moving the same into open position after the tamping means has completed compression action within the 65 box, means under control of the movable top

for rendering the operating means for the tamping means inoperative when said movable top has reached a predetermined open position, and an ejector mechanism automatically operating during the period between the completion of the compression action of the tamping means and when the operating means for said tamping means becomes inoperative. 70

8. A block press comprising, in combination, a mold box, a tamp having rectilinear movement within the mold box and provided with a part extending exteriorly thereof, an arm extending laterally from said part and supported for swinging movement in the same general direction as the direction of travel of the tamp and means operating independent of the arm for reciprocating the tamp. 75

9. A block press comprising, in combination, a mold box, a tamp having rectilinear movement within the mold box and provided with a part extending exteriorly thereof, an arm extending laterally from said part, a pivotally supported link in pivotal engagement with the free end portion of the arm, means for constantly urging said link in one direction and means operating independently of the arm for reciprocating the tamp. 85

10. A block press comprising, in combination, a mold box, opposed tamps having reciprocatory movement within the mold box, a rock arm operatively engaged with each of the tamps, a slide, means for reciprocating the slide, an operative connection between the slide and each of the rock arms for moving the rock arms in unison but in reverse directions and means operatively engaged with each of the tamps for urging the same in one direction angular to its direction of reciprocation to cause said tamp to have close contact with a wall of the mold box at all times during its reciprocatory movement. 100

11. A block press comprising, in combination, a mold box including a movable side wall, tamping means working within the box, means for operating said tamping means, and automatic means for moving said movable wall into open position, said last named means also serving as ejector means after said movable wall has been moved to a predetermined extent into open position. 110

12. A block press comprising, in combination, a mold box including a movable wall, tamping means working therein, a reciprocatory member for operating the tamping means, and automatic means operable from the reciprocatory member for moving the movable wall of the box into open position. 125

13. A block press comprising, in combi-

nation, a mold box including a movable wall, tamping means working therein, a reciprocatory member for operating the tamping means, automatic means operable from the reciprocatory member for moving the movable wall of the box into open position, means for locking the movable wall in closed position, and automatic means operable from the reciprocatory member for 10 releasing said locking means before the automatic means for moving the wall into open position becomes operative.

14. A block press comprising, in combination, a mold box including a movable wall, tamping means working therein, a reciprocatory member for operating the tamping means, automatic means operable from the reciprocatory member for moving the movable wall of the box into open position, 15 means for reciprocating said reciprocatory member, and automatic means to render said last named means inoperative when the movable wall has been moved to a determined point in open position.

25 15. A block press comprising, in combination, a mold box including a movable wall, tamping means working therein, a reciprocatory member for operating the tamping means, automatic means operable from the reciprocatory member for moving the movable wall of the box into open position, 30 means for reciprocating said reciprocatory member, and automatic means to render said last named means inoperative when the movable wall has been moved to a determined point in open position, said operating means becoming operative when the movable wall is returned to closed position.

16. A block press comprising, in combination, a mold box including a movable wall, tamping means working therein, a reciprocatory member for operating the tamping means, automatic means operable from the reciprocatory member for moving the 40 movable wall of the box into open position, an ejector mechanism, and means for operating said ejector mechanism from the movable wall when the movable wall moves into open position.

50 17. A block press comprising, in combination, a mold box, a tamping means working therein, means for operating said tamping means, automatic means for rendering said operating means inoperative at substantially the completion of a molding operation, and manual means operating independently of the automatic means to render said operating means inactive.

60 18. A block press comprising, in combination, a mold box, a tamp having rectilinear movement within the mold box, means for reciprocating the tamp, and means for constantly urging the tamp in one direction angular to its direction of re-

ciprocation to cause said tamp to have close 65 contact at all times with a wall of the mold box.

19. A block press comprising, in combination, a mold box including a movable top, tamping means working within the box, 70 means for operating said tamping means, and automatic means operated by said second named means for moving the top into open position and beyond a vertical center.

20. A block press comprising, in combination, a mold box including a movable top and a movable side wall, means common to the movable top and movable side wall for locking the same in working relation, tamping means working within the box, and automatically operating mechanism for releasing the movable top and movable side wall and moving the same into open position after the tamping means has completed compression action within the box.

85 21. A block press comprising, in combination, a mold box embodying a movable wall, tamping means working within the mold box, means for operating the tamping means including a shaft, coacting clutch 90 members mounted upon the shaft, one of said members being loose on the shaft and the other having movement in a direction lengthwise of the shaft, said first named member constituting a driving element for 95 the shaft, and means automatically operating when the tamping means is moved into non-compressing position to separate the clutch members.

100 22. A block press comprising, in combination, a mold box embodying a movable wall, tamping means working within the mold box, means for operating the tamping means including a shaft, coacting clutch members mounted upon the shaft, one of said members being loose on the shaft and the other having movement in a direction lengthwise of the shaft, said first named member constituting a driving element for the shaft, and means automatically operating when the 105 tamping means is moved into non-compressing position to separate the clutch members, said last named means being under control of the movable wall.

115 23. A block press comprising, in combination, a mold box embodying a movable wall, tamping means working within the mold box, means for operating the tamping means including a shaft, coacting clutch members mounted upon the shaft, one of said members 120 being loose on the shaft and the other having movement in a direction lengthwise of the shaft, said first named member constituting a driving element for the shaft, means automatically operating when the tamping means is moved into non-compressing position to separate the clutch members, and means for normally maintaining the clutch 125

members in working engagement, said last named means functioning when the movable wall is in closed position.

24. A block press comprising, in combination, a mold box, tamping means working therein, a reciprocating member for operating the tamping means, a shaft operatively engaged with the reciprocating member for operating the same, a driving means coacting with the shaft and embodying relatively movable clutch members operating to rotate the shaft when said members are in working engagement, and means operating upon movement of the reciprocating member in one direction to disengage the clutch members.

25. A block press comprising, in combination, a mold box, tamping means working therein, a reciprocating member for operating the tamping means, a shaft operatively engaged with the reciprocating member for operating the same, a driving means coacting with the shaft and embodying relatively movable clutch members operating to rotate the shaft when said members are in working engagement, means operating upon movement of the reciprocating member in one direction to disengage the clutch members, said mold box including a movable wall, and means operated from the movable wall when moved into closed position for returning the clutch members into working engagement.

26. A block press comprising, in combination, a supporting frame, a mold box mounted thereon and including a movable wall, a latch carried by the movable wall, a part carried by the frame with which the latch coacts for holding the movable wall in closed position, a tamping means, a reciprocating member for operating the tamping means, means operable upon movement of the reciprocating member in one direction for releasing the latch, and automatic means operating to move said wall into open position after the latch is released.

27. A block press comprising, in combination, a supporting structure, a mold box mounted thereon and including a movable wall, an arm secured to said wall and pivotally engaged with the structure whereby said wall has swinging movement into open or closed position, a tamping means working within the box, a reciprocating member for operating said tamping means, and a bar moving with the reciprocating member and engaging the arm of the movable wall after the reciprocating member has had predetermined movement in one direction for swinging said wall into open position.

28. A block press comprising, in combination, a mold box including two movable walls, tamping means working therein, automatic means for moving one of the walls into open position, and means operable from said wall, when moving into open position, to move the second wall into open position.

29. A block press comprising, in combination, a mold box including two movable walls, tamping means working therein, automatic means for moving one of the walls into open position, and means operable from said wall, when moving into open position, to move the second wall into open position, said last named means also serving as ejector means after said second movable wall has been moved to a predetermined extent into open position.

30. A block press comprising, in combination, a mold box including two movable walls, tamping means working therein, automatic means for moving one of the walls into open position, means operable from said wall, when moving into open position, to move the second wall into open position, and automatic means for returning the second movable wall into closed position.

In testimony whereof I hereunto affix my signature.

JOSEPH VOGT.
